UNITED STATES PATENT OFFICE

2,613,738

WINDOW RAISING AND CLEANING UNIT

William A. Bowman, Baltimore, Md.

Application September 11, 1950, Serial No. 184,318

4 Claims. (Cl. 160—11)

1

This invention relates to buildings and other occupational structures and more particularly to the window construction for same. Further in the window construction considered particular attention is directed to that embodying sashes that open outwardly in jack-knife manner and operate along the lines indicated in my copending application Serial Number 81,375, filed March 14, 1949, now abandoned and in my Patent Number 2,513,278 to which reference is made.

In the particular construction shown in the previous application, the window structure includes an adjustable frame and a plurality of sashes that fold up into various angular positions outside of the normal plane of the frame window structure. The sashes are hinged together at the edges where they meet to enable this to be done. They are opened up on their hinges manually and held in any position selected by frictionally engaging the frame with set screws adjustably projecting from the sashes into the frame and by tightening both together. However, the objection to this specific type of adjustment is that it requires considerable muscular effort to raise or adjust the sashes to a jack-knife position and the frictional engagement is not as positive and safe from unloosening, as desired. In this invention, the adjustment is of different construction, and is of a type that lends itself readily to power operation. It employs a worm and link mechanism having a powerful mechanical movement that is controllable for close adjustment and against slippage while adding appreciably to the appearance of the window structure.

This invention has amongst its objects to provide a new and improved adjusting mechanism for opening windows, that will avoid one or more or the disadvantages and limits of the prior art.

Another object of the invention is to provide a new and improved adjusting and pane wiping mechanism for window sashes opening in jack-knife fashion that will be powerful in action, and effective in operation.

A further object of this invention is to provide a new and improved adjusting mechanism for window sashes opening in jack-knife fashion that can be power operated.

An additional object of the invention is to provide a new and improved adjusting and pane cleaning mechanism for windows that will be simple in construction, economical to manufacture and assemble, and effective in operation.

Other objects will become apparent as the invention is more fully set forth.

For a better understanding of the invention and 55 joint. However, the lower member 32 of the sash

the objects thereof reference is made to the appended drawings wherein a preferred form of the invention is illustrated. These drawings together with the following outline emphasize the principles and operation of the mechanism, while the claims indicate the scope of the invention.

Referring to the drawings:

Figure 1 is a front view of a window structure embodying this invention, with the sashes in closed position;

Figure 2 is a sectional elevation taken along line 2—2 of Figure 1;

Figure 3 is a front view similar to Figure 1, except the sashes are in raised position;

Figure 4 is a sectional view taken along line 4—4 of Figure 3;

Figure 5 is an enlarged detail of the raising and lowering mechanism and mechanism for operating the window cleaning device;

Figure 6 is a sectional view taken along line 6—6 of Figure 5 showing the sash raising and lowering mechanism;

Figure 7 is a sectional view taken along line 7—7 of Figure 5, showing the method of attaching the window cleaning device to the sash;

Figure 8 is a typical sectional view taken through the clutch shifter;

Figure 9 is a typical sectional view taken through the combined bevel gear clutch; and

Figure 10 is a diagrammatic wiring diagram.

Similar reference characters refer to similar parts throughout the drawings.

In the particular construction shown in the drawings, a conventional window frame 10 of rectangular form is set in a suitable opening in the wall 11 of a building. The frame is modified by eliminating the usual channels in which the window ordinarily slides up and down, and in its place a bar of molding 12 is installed against which the window sashes 15 and 16 can butt up. The window sashes instead of sliding up and down in opening and closing, move in a jack-knife movement outwardly. This is provided for by the upper member 15 of the sash being arranged with upper hinges 13 on both sides, and attached to the inside surface 14 of the molding bar 12. This enables the sash 15 to swing outwardly in a free and easy manner. The bottom member of the sash 15 also has half 18 of a hinge 17 attached to it. The other half 19 of the hinge 17 is attached to the upper member of the lower sash 16 and a pivotable joint made between them by a suitable rounding of the members to rotate with one another. This is on the principle of the ball

16 is kept close to the window frame 10 by means of ribs 33 in the molding 12. These ribs extend laterally from the molding 12 and guide the pins 34 in the lower member 32, vertically up and down. The upper member 15 of the sash moves in conjunction with the lower member of the sash 16 from straight line alignment to apexed form, depending on the amount the lower member 16 of the sash is raised.

The raising and lowering of the sashes is done through the use of a motor mechanism. The mechanism consists of a pair of saddles 20 that are attached to the upper member of the sash 16.

Saddles 20 carry segment teeth 21 as shown. These teeth mesh with the teeth on a gear 22, that in turning moves the saddles through a predetermined arcuate path and the saddles in turn carry the sashes through the same path assuming the straight or apexed positions already mentioned. The gear 22 is mounted and freely rotatable on a shaft 23 that extends horizontally across the sash 15 as indicated, and has clutch fingers 24 projecting from one side of it. The shaft is continuously rotated by a motor 25 through a worm 26 and a worm gear 27. A clutch 28 is operated by a shifter 29 and is keyed at 35 to the shaft 23 so as to rotate continuously with it. Clutch 28 has teeth 30 on opposite sides adapted to engage in the fingers 24 of the gear 22 on one side and fingers 31 on the opposite side. The fingers 31 engage fingers 36 formed on a bevel gear 37. The bevel gear 37 is meshed with two other bevel gears 38 that rotate individually screw rods 39 on each side of sashes 15 and 16. Suitable supports 40 hold the rods 39 in place along the vertical members of the sashes.

The sashes 15 and 16 have panes 41 and 42 of glass respectively set in them. The rods 39 carry screwed holders 43 which carry rubber squeegees 44 of a pair of window cleaners employed for cleaning the window panes on the outer and inner sides of the windows. When the rods are rotated by the bevel gears operated by the shaft 23 in clutched engagement therewith, they incidently move the window cleaners with them. The direction of movement depends on the counter-clockwise or clockwise operation of the shaft. The window cleaners are used when the opening and closing mechanism of the windows is not in operation, this can be appreciated by noting the positions of the clutch fingers and the clutch. Clutches 45 have fingers 46 for engaging the fingers 36 on bevel gear 37 and fingers 24 on gear 22. The clutches 46 and 28 are connected by shifter 29 and may be shifted to neutral or to the left or right of the window as required. The shifter is operated from inside the building through the use of the handle mechanism 47. The screw rods 39 with the gears 37 and 38 are so arranged that they can be moved through an arcuate path without obstruction and interference with the jack-knife movement of the sashes 15 and 16. The structure of the members of the sashes 15 and 16 are slotted out and otherwise formed to permit the cleaning operations without difficulty.

The motor is operated to run in either direction, through the use of the double-throw switch 48 and limit switches (not shown) may be provided if desired to shut off the current at suitable points to prevent the windows being opened too much or the mechanism from being stressed unduly. The diagram indicates the wiring 50 preferably used for the motor circuit.

The mechanism used in this invention is par-

ticularly desirable for future building operations, wherein the up and down windows are displaced by the more modern jack-knife type. With this invention the window opening is positively controllable to any degree of opening in a positive and convenient manner and in all such positions may be cleaned by motive power, eliminating the use of human window cleaners ordinarily employed. This is particularly desirable because the work of human window cleaners is highly dangerous to themselves and others. These men in their work are a source of anxiety and disturbance to office workers and on-lookers and greatly interfere with the work and commercial concentration of others. Further by the use of this mechanism and its convenience the window panes can be cleaned off frequently and economically. Also the window may be cleaned in its open or closed position effectively. This is not feasible by ordinary human cleaning methods. The advantages of the jack-knife operation are discussed in previous patents.

The sashes are provided with roller screens 55 and 66 which move with the sashes when they are raised or lowered and keep the window opening closed against the admission of insects and the like therethrough.

While but one general form of the invention is shown in the drawings and described in the specifications, it is not desired to limit this application for patent to this particular form as it is appreciated that other forms of construction could be made that would use the same principles and come within the scope of the appended claims.

Having thus described the invention, what is claimed is:

1. In operating mechanism for windows, the combination with a window frame of an upper sash pivoted laterally at its upper end to the frame, a lower sash, hinge means between the sashes, a pair of geared quadrants secured to the lower sash at opposite sides thereof, a shaft carried by and extending transversely of the upper sash, a motor for rotating said shaft, a gear freely mounted on said shaft at each end thereof and meshing with said quadrants, clutching means for meshing said gears and said shaft, means for guiding the lower end of the lower sash for reciprocating movement in the frame, and means for operating said clutching means to cause rotation of said gears and quadrants when the shaft rotates, to move the sashes from alignment to a jack-knife position, the motor being reversible to move the sashes from jack-knife position to alignment while the gears and quadrants are in mesh.

2. An operating mechanism as set forth in claim 1, wherein said clutch means include a pair of elements at opposite ends of the shaft keyed to and slidably on said shaft, said elements having teeth and said freely mounted gears having axial fingers engageable with said teeth, and the means for operating the clutching means comprise a connection between said pair of elements and a handle to actuate said connection.

3. In operating mechanism for windows, the combination with a window frame of an upper sash pivoted laterally at its upper end to the frame, a lower sash, hinge means between the sashes, a pair of geared quadrants secured to the lower sash at opposite sides thereof, a shaft carried by and extending transversely of the upper sash, means for rotating said shaft, a gear freely mounted on said shaft at each end thereof and

meshing with said quadrants, means for guiding the lower end of the lower sash for reciprocating movement in the frame, a pair of squeegees, each of which is reciprocable on each glass pane, gearing means between said shaft and said squeegees, and unitary clutching means selectively operable in one position to mesh the freely mounted gears with said shaft to open the window in jack-knife fashion, and operable in another position, to mesh said gearing means with said shaft, to operate the 10 squeegees.

4. An operating mechanism as set forth in claim 3, wherein said gearing means between the shaft and the squeegees include a pair of bevel gears near opposite ends of the shaft, loosely mounted thereon, a pair of bevel gears meshing with each of the first mentioned bevel gears, one

5 gear of the second mentioned pair being secured on the upper sash and the other on the lower sash, a screw rod secured at one end to each of said last mentioned bevel gears, and a squeegee holder for each pane riding on a pair of parallel screw rods.
